UNITED STATES PATENT OFFICE.

FRED D. SWEET, OF PITTSBURG, PENNSYLVANIA, ASSIGNOR, BY MESNE ASSIGNMENTS, TO THE STIRLING COMPANY, OF JERSEY CITY, NEW JERSEY, A CORPORATION OF NEW JERSEY.

MANDREL FOR SHAPING HOLLOW OR TUBULAR WROUGHT-METAL ARTICLES.

SPECIFICATION forming part of Letters Patent No. 693,186, dated February 11, 1902.

Application filed April 12, 1901. Serial No. 55,508. (No model.)

To all whom it may concern:

Be it known that I, FRED D. SWEET, a resident of Pittsburg, in the county of Allegheny and State of Pennsylvania, have invented a new and useful Improvement in Mandrels for Shaping Hollow or Tubular Wrought-Metal Articles; and I do hereby declare the following to be a full, clear, and exact description thereof.

10 My invention relates to a mandrel for use in shaping hollow or tubular metal articles, such as serpentine boiler-headers and other articles having an irregular shape.

Serpentine boiler-headers and similar articles are made from comparatively heavy metal, and as such articles are irregular in shape considerable difficulty has been experienced in forming them of wrought-iron or steel. By reason of the thickness of the 20 metal composing such articles it requires heavy pressure to properly shape the same, and in order to prevent the collapse of the tube during the shaping process it is necessary to use an internal support or mandrel for the same. By reason of the great irregularity in the shape of these articles difficulty has been experienced in providing a suitable internal support or mandrel which will offer sufficient resistance to the action of the 25 external forging or pressing dies and which nevertheless is capable of being withdrawn or removed from the header or other article after the same is shaped. Heretofore serpentine headers and similar articles have 30 been made of wrought metal only by the use of complicated sectional and collapsible mandrels, which were inserted in the tube and after the same was shaped were then collapsed and withdrawn therefrom.

40 It is the object of my invention to provide a mandrel for this purpose which is simple, strong, and comparatively inexpensive and which can be easily inserted in the tube and withdrawn from the header or other article 45 after the same has been shaped.

To this end it comprises a body or support of the proper shape to form the desired article and which is composed of a few simple and easily-assembled sections so constructed 50 that they can be secured together to form a

rigid body, which is inserted in the tube and is adapted to have the walls of the latter pressed down upon the same to shape the article, and which sections can thereafter be readily withdrawn from the finished article.

In the accompanying drawings, Figure 1 is a longitudinal vertical section of my improved mandrel. Fig. 2 is a transverse section of the same. Fig. 3 is a longitudinal section illustrating the mandrel shaped to form 60 tubular articles of sharper curve than illustrated in Fig. 1. Fig. 4 is a transverse section of the same. Fig. 5 is a plan view of either the mandrel shown in Fig. 1 or Fig. 3. Fig. 6 is a longitudinal sectional view of the mandrel formed in longitudinal sections to permit the application of a diaphragm to the header or other tubular article. Fig. 7 is a transverse vertical section of the same. Fig. 8 is a longitudinal vertical section through 70 the shaping-dies, tube, and inclosed mandrel; and Fig. 9 is a vertical transverse section of the same.

In the drawings I have shown my invention applied in the formation of serpentine boiler-headers, and the mandrel comprises the body 1, having substantially flat and parallel side faces 2 and sinuous or corrugated top and bottom faces 3. This mandrel is adapted to be inserted in a rectangular tube 4, which 80 has first been properly heated and, together with the same, is placed in the dies 5, whereby the tube is pressed down upon the mandrel to conform to the shape thereof, after which the said mandrel is removed. The dies 85 5 comprise a lower stationary die 6, having a sinuous working face 7, and an upper movable die 8, which is provided with a similar sinuous working face 9, said upper die being moved, preferably, by means of a hydraulic 90 cylinder (not shown) or by means of a cam, eccentric, or any other suitable mechanism. Formed integrally therewith or suitably secured to the bottom die 6 is the plain-faced stationary side die 10, and opposite this is a 95 plain-faced movable side die 11, the same being moved, preferably, by means of a hydraulic cylinder or other equivalent mechanism, as above stated, although it may be moved by wedges or similar devices. In the 100

operation of these dies the mandrel inclosed in the heated tube is placed on the bed-die 6, and the side die 11 is moved up to confine the same between said die 11 and the die 10, 5 after which the die 8 is brought down to press the walls of the tube down into the depressions or corrugations on the upper and lower faces of the mandrel 1. In this operation it is necessary that the metal in the side walls 10 of the tube between the points 12 and 13 be upset into the metal between the points 13 and 14, or, in other words, that the height of the side walls of the tube be reduced an amount equal to the distance between the 15 points 12 and 13. In order to secure a proper upsetting of this metal and leave the side walls smooth and of uniform thickness, it is preferable that the side die 11 be at first brought but lightly against the side of the 20 tube 4, and after the top die 8 has been brought down to upset the side walls of the tube the side die 11 is pressed firmly against the said tube, thereby smoothening out any bulges or unevenness in the side walls of the 25 tube, and it may even be found desirable in carrying out the invention that the dies 8 and 11 be given alternate slight inward and outward movements in order to secure the proper shaping and upsetting of the side walls 30 of the tube. For this reason it is preferable that the side die 11 be moved by a hydraulic cylinder or equivalent mechanism, as above stated.

The invention so far described is not my 35 own, but is the invention of James P. Sneddon, as described and claimed in applications, Serial Nos. 55,541 and 55,548, filed April 12, 1901.

My invention relates to the specific form of 40 mandrel which is to be used with the dies 5 and in the manner above stated and will now be described.

My mandrel 1 comprises a series of blocks 45 or sections 15 15^a 15^b &c., all of which are similar and comprise the main body of the mandrel and two end blocks or sections 16 and 17, all of these blocks or sections being provided, preferably, with an opening or hole 18 passing therethrough, which when the 50 blocks are assembled aline with each other to receive the tie-rod 19, the same being provided on one end with a head 20 and is screw-threaded at its opposite end to receive the nut 21, by means of which tie-rod and nut the 55 said blocks are locked immovably together to form a rigid body. It is obvious that in place of the tie-rod 19 and nut 21 various other means may be used to lock the blocks or sections together, and that my invention is not 60 limited in this particular.

Each of the blocks 15 15^a 15^b, &c., is of a general triangular shape having two flat faces 22 and the third face being formed with the convex-curved portion 23 and the concave-curved portions 24 24. The end blocks 16 and 17 are so shaped that they will fit against the ends of the blocks 15 15^a 15^b, &c., and

complete the mandrel, said end blocks being provided with straight outer faces, as at 25, to provide suitable seats for the head 20 and nut 21, as will be readily apparent.

In order that the blocks 15 15^a 15^b, &c., may be removed from the shaped serpentine header or other article, it is necessary that the faces 22 of said blocks should bear a certain definite relation to the curved portions 23 24 thereof, as will now be explained. The concave portions 24 of the blocks are struck about the points *a a' a''*, &c., as centers, and the convex portions 23 of said blocks are struck about the points *b b' b''*, &c., as centers, and the said blocks are divided at the middle of the convex portions 24, as at 26. The points *c c' c'' c'''*, &c., represent the points where the convex curves 23 merge into the concave curves 24, and if through these points lines be drawn which are at right angles to both the radii *a c* and *b c*, such as the lines *c d c' d' c'' d'' c''' d'''*, &c., these lines will be tangential to both the curves 23 and 24. The side faces 22 of the blocks are formed parallel to these tangential lines just specified. For instance, in block 15 the side face *d e'* is parallel to the tangent *c' d'*, and the face *d' e'* of said block is parallel to the tangent *c d* of the same block, or, what is equivalent thereto, is a projection of the tangent *c'' d''* of the block 15^a. By following this principle of construction the said blocks can be readily removed from the finished header or other article, it being impossible for the same to become bound therein. For instance, after the shaping of the header on the mandrel the tie-rod 19 is removed, and after the blocks 16 and 15^c are removed it will be apparent that the block 15 can be moved in a straight line in the direction of the arrow 26^a, and inasmuch as the face *d' e'* of said block is parallel to the tangent *c d* it will be impossible for the block to be bound by the curved side walls of the header or other article.

This principle of construction will hold good no matter what the shape or curvature or degree of curvature on the sinuous faces of the mandrel may be. In Fig. 3 the curves 115 on the faces of the mandrel are shown much sharper; but it will be readily observed that the blocks nevertheless cannot become bound in the tube. In order, however, to facilitate the removal of the blocks, the apices of said blocks are removed, as shown at 27.

The corrugations 23 24 on the faces of the mandrel are shown as extending obliquely or at an angle across said faces, and the meeting lines 26 of the blocks will extend at the same angle as shown in Fig. 5. This is to adapt the mandrel to form headers for boilers having inclined water-tubes; but in case the header is to be used for a boiler having horizontal water-tubes the corrugations 23 24 130 and meeting lines 26 of the blocks will extend straight across the faces of the mandrel. The principle of constructing these blocks, however, will remain unchanged.

In certain forms of boiler-headers—as, for instance, in the Niclausse boiler—it is necessary to provide the same with a longitudinal diaphragm, and this may be done by forming the mandrel in two longitudinal sections, placing the shaped diaphragm between the same, inserting the mandrel-sections with the interposed diaphragm in the squared or rectangular tube, and then by means of the dies shown 5 pressing the walls of said tube down upon the mandrel, thereby shaping the header and also pressing the said walls firmly against the edges of the shaped diaphragm, and inasmuch as the latter is preferably formed slightly 10 wider than the mandrel the edges thereof will become embedded in the walls of the tube and be held firmly in place. This method is the invention of James P. Sneddon, as described and claimed in his application, Serial No. 15 55,542, filed April 12, 1901, and I do not, of course, claim the same; but in Figs. 6 and 7 I have shown my specific form of mandrel adapted for carrying out this process. As shown, the mandrel is formed in two sections 20 25 28, each of which is formed of blocks constructed and assembled as shown in Figs. 1 and 3 and united by means of tie-rods and nuts, as in said figures. The diaphragm 29, which has been cut to proper shape and which 30 35 is jogged or stepped, as shown at 30, in order to provide the faces 31, which will be at right angles to the inclined water-tubes of the boilers, is placed between the sections 28 of the mandrel, and the latter are united, as by 40 45 means of the links 32, which links are provided with openings at their opposite ends for receiving the tie-rods 19, by means of which the sections 28 are secured together and prevented from endwisedisplacement. This mandrel, together with the interposed diaphragm, is then placed in the tube, and the operation as above described is carried out, after which the tie-rods 19 are removed and the blocks or sections of the mandrel removed from the finished header in the manner above described 50 in connection with the mandrel shown in Figs. 1 and 3.

To facilitate the removal of the blocks composing the mandrel, it is desirable to form the same with the openings or recesses 33, which are adapted to be engaged by the hooked end of a rod, by means of which the said blocks can be drawn out of the header.

The mandrel shown and described presents a perfectly rigid support to the thrust of the forging or shaping dies, and consequently insures the header or other article being properly formed on the same, there being no possibility that the article can collapse at one or more points. At the same time this mandrel is so constructed that it is impossible for the sections thereof to become bound in the header or other article; but the same can be readily removed therefrom and can again be quickly 55 60 65 and easily assembled and used in the formation of other headers.

While I have shown my mandrel applied in

the formation of serpentine boiler-headers, I wish it understood that the invention is not limited thereto, but that the same can be applied in the formation of other tubular metal articles or shapes which are provided with at least one sinuous or curved face by suitably changing the shape of the mandrel and the compressing-dies, as will be readily understood. 70 75

What I claim as my invention, and desire to secure by Letters Patent, is—

1. A mandrel for use in shaping wrought-metal headers or other tubular articles, the same comprising a body composed of a series of transverse sections and means for immovably securing said sections together to form a rigid body, said mandrel being adapted to be inserted in the tube and have the latter 80 85 pressed thereupon and to be then removed therefrom.

2. A mandrel for use in shaping wrought-metal headers or other tubular articles, the same comprising a body provided with a 90 curved or sinuous face and composed of a series of sections and means for immovably securing said sections together to form a rigid body, said mandrel being adapted to be inserted in the tube and have the latter pressed 95 thereupon and to be then removed therefrom.

3. A mandrel for use in shaping wrought-metal headers or other tubular articles, the same comprising a body provided with oblique transverse corrugations and composed of a 10 series of sections, and means for immovably securing said sections together to form a rigid body, said mandrel being adapted to be inserted in the tube and have the latter pressed thereupon and to be then removed therefrom. 105

4. A mandrel for use in shaping wrought-metal headers or other tubular articles, the same comprising a body having a curved or sinuous face, said body being composed of a series of sections the meeting faces of which 110 are parallel to the tangents to the points where the concave curves merge into the convex curves, and means for securing said sections together.

5. A mandrel for use in shaping wrought-metal headers or other tubular articles, the same comprising a serpentine body composed of a series of sections the meeting faces of which are parallel to the tangents to the points where the concave curves of the body merge 115 120 into the convex curves, and means for securing said sections together.

6. A mandrel for use in shaping wrought-metal headers or other tubular articles, the same comprising a serpentine body provided 125 with oblique corrugations and composed of a series of sections the meeting faces of which are parallel to the tangents to the points where the concave curves of the body merge 130 into the convex curves, and means for securing said sections together.

7. A block for a sectional mandrel for use in shaping wrought-metal headers or other tubular bodies, the same being of substantially

- rectangular shape and having one side formed on concave and convex meeting curves, and two straight sides which are parallel to the tangents drawn through the meeting-points 5 of the convex and concave curves on the first-named side.
8. A block for a sectional mandrel for use in shaping wrought-metal headers or other tubular articles, the same having flat parallel 10 side faces and being substantially rectangular in shape, and having one side formed on concave and convex meeting curves, and two straight sides which are parallel to the tangents drawn through the meeting-points of 15 the convex and concave curves on the first side, and which are oblique or at an angle to the parallel side faces of said block.
9. A block for a sectional mandrel for use in shaping wrought-metal headers or other tubular articles, the same being of substantially 20 rectangular shape and having one side formed on concave and convex meeting curves, and two straight sides which are parallel to the tangents drawn through the meeting-points of 25 the convex and concave curves on the first side, said block being provided with an opening passing therethrough for receiving a tie-rod.
10. A block for a sectional mandrel for use in shaping wrought-metal headers or other tubular articles, the same being of substantially 30 rectangular shape and having one side formed on concave and convex meeting curves, and two straight sides which are parallel to the tangents drawn to the meeting-points of the 35 convex and concave curves on the first-named side, said block being provided with a recess for receiving a hook for withdrawing the same from the tube.
11. A mandrel for use in shaping wrought-metal headers or other tubular articles, the same comprising a body having a curved or 40 sinuous face, said body being composed of a series of sections, said sections being divided 45 at the middle of the concave-curved portions of the face of the body and the meeting faces of said sections being parallel to the tangents to the points where the concave curves merge into the convex curves, and means for securing 50 said sections together.
12. A mandrel for use in shaping wrought-metal headers or other tubular articles, the same comprising a body having a curved or 55 sinuous face, said body being composed of a series of sections, the meeting faces of which are parallel to the tangents to the points
- where the concave curves merge into the convex curves, and a tie-rod passing through said sections for removably securing the same together. 60
13. A mandrel for use in shaping wrought-metal headers or other tubular articles, the same comprising a body composed of a series of transverse sections provided with alining openings, and a tie-rod passing through said 65 openings for rigidly securing said sections together.
14. A mandrel for use in shaping wrought-metal headers or other tubular articles provided with a diaphragm, the same comprising 70 two longitudinal sections each composed of a series of blocks, means for immovably securing said blocks together, and means for uniting said longitudinal sections at their ends.
15. A mandrel for use in shaping wrought- 75 metal headers or other tubular articles provided with a diaphragm, the same comprising two longitudinal sections provided with transverse corrugations, each section composed of a series of blocks, means for immovably securing said blocks together, and means for uniting said longitudinal sections at their ends. 80
16. A mandrel for use in shaping wrought-metal headers or other tubular articles provided with a diaphragm, the same comprising 85 two longitudinal sections, each having a curved or sinuous face and composed of a series of blocks the meeting faces of which are parallel to the tangents to the points where 90 the concave curves merge into the convex curves, means for securing said blocks together, and means for uniting said longitudinal sections at their ends.
17. A mandrel for use in shaping wrought- 95 metal headers or other tubular articles having a diaphragm, the same comprising two longitudinal sections of serpentine form, said sections being composed of a series of blocks the meeting faces of which are parallel to the tangents to the points where the concave curves of the body merge into the convex curves, means for immovably securing said blocks together, and means for uniting said longitudinal sections at their ends. 100
